UNITED STATES PATENT OFFICE.

CHARLES W. PEARSALL, OF SYRACUSE, NEW YORK.

DESIGN FOR A HOSE-NOZZLE.

SPECIFICATION forming part of Design No. 19,908, dated June 17, 1890.

Application filed May 9, 1890. Serial No. 351,188. Term of patent 14 years.

To all whom it may concern:

Be it known that I, CHARLES W. PEARSALL, a citizen of the United States, residing at Syracuse, in the county of Onondaga and State of New York, have invented and produced a new and original Design for Hose-Nozzles; and I do hereby declare the following to be a full, clear, and exact description of the same, reference being had to the accompanying drawing, forming a part thereof.

My invention consists of a new design for a hose-nozzle; and its object is to give to such an article a highly ornamental appearance and configuration, and by which it can be readily distinguished from similar articles in the market.

It is illustrated in the accompanying drawing, which is a side elevation.

Referring to the drawing, A is a cylinder, provided at its outer end with a bead b, and terminating at its inner end in an ovoidal section C.

D is a smooth band, having the form of an ovolo, with rounded edges and ends d. Next to the band D is a milled band E, having smooth curved edges e.

F is a hemispherical section, provided with a cylindrical neck g and a milled head H. The head H is connected to the neck g by an ovoidal section i. The milled band E is placed on and extends over the section F. The band E has the greatest globular projection next the part D, then the part F, the part C the next. The bead b and the head H are next

in order, and have about the same projection, 35 and then the cylindrical parts A and g, which are also of the same projection.

The entire design consists of the parts thus described and shown; but the distinctive and predominant feature of my design consists of 40 the parts D, E, F, g, H, and i, which can be used with or without the other particular forms of parts.

What I claim is—

1. The design for a hose-nozzle herein shown 45 and described, comprising the cylinder A, provided at its outer end with a bead b and at its inner end with an ovoidal portion C, the band D, having the form of an ovolo with rounded edges and ends d, the milled band 50 E, the hemispherical section F, the neck g, and the milled head H, having the ovoidal section i, as set forth.

2. In the design for a hose-nozzle herein shown and described, the smooth band D, 55 having the form of an ovolo, the milled band E, having the rounded edges e, the hemispherical section F, the cylindrical neck g, and a milled head H, provided with the ovoidal section i, as set forth.

In testimony whereof I affix my signature, in presence of two witnesses, this 5th day of May, 1890.

CHARLES W. PEARSALL.

Witnesses:

WALTER WELCH,
CHARLES L. HOFFMAN.
